UNITED STATES PATENT OFFICE.

WILLIAM W. NEUER, OF WILKES-BARRE, PENNSYLVANIA.

TRANSOM-LIFTER.

SPECIFICATION forming part of Letters Patent No. 355,200, dated December 28, 1886.

Application filed October 1, 1886. Serial No. 215,093. (No model.)

To all whom it may concern:

Be it known that I, WILLIAM W. NEUER, of Wilkes-Barre, in the county of Luzerne and State of Pennsylvania, have invented certain 5 new and useful Improvements in Transom-Lifters; and I do hereby declare the following to be a full, clear, and exact description of the invention, such as will enable others skilled in the art to which it appertains to make and use 10 of the same.

My invention relates to devices for operating transoms, casements, shutters, &c.; and the object of my invention is to provide means whereby the transom or other swinging structure may be held either wholly or partially 15 open or closed without any possibility of accidental derangement of the operating and holding connections.

For the above purposes my invention consists in certain peculiar and novel features of construction and arrangement, as hereinafter described and claimed.

In order that my invention may be fully understood, I will proceed to describe it with 25 reference to the accompanying drawings, in which—

Figure 1 is a perspective view of a transom with my improvements applied thereto. Fig. 2 is a transverse vertical section of the same. 30 Fig. 3 is a view similar to Fig. 2, but showing a modified form of the connections. Fig. 4 is a view, partially in longitudinal section, illustrating the connections shown in Figs. 1 and 2. Fig. 5 is a view similar to Fig. 4, but 35 showing the connections illustrated in Fig. 3.

In the said drawings A designates the frame of a transom or casement, and B designates the transom or casement proper, the latter being connected to the frame A by hinges b, or in 40 any other suitable or preferred manner. Upon the inner side of one end of the frame A is secured, by screws or other suitable devices, a plate, C, which extends vertically upon the frame, and which is formed with a number of 45 holes or apertures, c, extending in straight alignment upon the plate.

D designates an arm, which is attached loosely at one end to a ring-bolt, d, upon the inner side of the transom, and at one end of 50 the latter contiguous to the plate C. The inner or free end of the arm D is formed with

an eye or loop, d', to receive the operator's finger, and at its extremity said arm is bent outward at right angles to the main portion of the arm, as shown at d'', so as to enter one or 55 the other of the holes c in the plate C. Upon the inner side of the lower or outer corner of the transom B is secured an angle-plate, E, having in its inwardly-extending portion e an aperture or eye, e', the position of plate E being such that when the transom is closed the eye or aperture in the angle-plate shall register with the lowest hole in the plate C. When the transom is thus closed, the end d'' of arm D is inserted through the eye e' and lowest 65 hole, c, and thus the transom is locked in closed position.

The bent end d'' of arm D is formed with a shoulder, d'', which, when the bent end is inserted in either of the holes c, engages the under side of the margin of such hole and prevents any accidental displacement of said arm from the hole, so that the transom is held securely when either wholly or partially open or closed. In the modified construction shown 70 in Fig. 3 the bent end d'' of arm D is formed with an annular shoulder, d'', which does not enter the holes c of plate C, but lies beneath a swinging plate, C', pivoted at one end to the upper end of plate C, and having a series of 75 notches, c', in its outer edge to embrace the end d'' outside of the shoulder d'', and thus lock the free end of the arm D when the transom is either wholly or partially open or closed. In this instance the arm D is attached at its 80 outer end to an angle-plate, f, similar in form to the angle-plate E, before described.

In order to sustain the transom when raised to its utmost limit, a hole is formed in one of the end jambs of the frame A, and a ferrule, 90 g, is inserted into said hole to receive the end d'' of bar D.

It will be readily seen that the plate C may be dispensed with, and that holes with ferrules g may be formed directly in the ends of the 95 casing at the points occupied by the holes c in the plate C without departing from the spirit of my invention.

The devices embodied in my invention are simple in construction and readily operated, 100 and serve to hold the transom securely in either of its desired positions.

Having thus described my invention, what I claim as new, and desire to secure by Letters Patent, is—

1. The combination, with the apertured plate 5 and its notched swinging plate, of the swinging arm secured to the transom and provided with the annular shoulder, substantially as specified.
2. The combination, with the transom carrying the angle-plate E, with its eye e', and the frame carrying the apertured plate C, with

its swinging notched plate C', of the holding-arm D, having the annular shoulder d', substantially as and for the purpose described.

In testimony whereof I have hereunto subscribed my name in the presence of two subscribing witnesses.

WILLIAM W. NEUER.
